(57) CLAIM

The ornamental design for a cosmetic container, substantially as shown and described.

DESCRIPTION

FIG. 1 is a perspective view of a cosmetic container showing my new design;

FIG. 2 is a front elevational view thereof;

FIG. 3 is a rear elevational view thereof;

FIG. 4 is a left elevation view thereof, the right side view being a mirror image thereof;

FIG. 5 is top plan view thereof;

FIG. 6 is bottom plan view thereof;

FIG. 7 is an exploded perspective view thereof in an open state;

FIG. 8 is a front elevational view of a basic container thereof;

FIG. 9 is a rear elevational view of the basic container thereof;

FIG. 10 is a left elevation view of the basic container thereof, the right side view being a mirror image thereof;

FIG. 11 is a top plan view of the basic container thereof;

FIG. 12 is a side elevational view of a cap thereof; and,

FIG. 13 is a bottom plan view of the cap thereof.

The bottom and cap of the cosmetic container are disclosed separately for convenience of illustration.
